UNITED STATES PATENT OFFICE.

DUNCAN CAMERON, OF RANDOLPH, NEW YORK.

PIN-AND-BOX JOINT FOR STONE-DRILLS.

SPECIFICATION forming part of Letters Patent No. 295,347, dated March 18, 1884.

Application filed August 3, 1883. (No model.)

To all whom it may concern:

Be it known that I, DUNCAN CAMERON, a citizen of Ontario, Canada, residing at Randolph, in the county of Cattaraugus and State 5 of New York, have invented certain new and useful Improvements in Pin-and-Box Joint Stone-Drills; and I do hereby declare the following to be a full, clear, and exact description of the invention, such as will enable others skilled in the art to which it appertains to 10 make and use the same.

This invention relates to the construction of tools for drilling oil or other deep-bored wells; and it consists in improvements on the screw- 15 joint by which the drill or other tool is attached to the drill-stock, which joint is commonly called the "pin and box." It is at this point that the tool almost always breaks while in use, and many forms have been devised to 20 add strength there without increasing the size. One form employed for this purpose consisted in making the pin and box with two separate screws of equal pitch but unequal diameter, or, in other words, making an inner pin and 25 box.

The present invention consists in improvements upon the said construction. The difficulty found with the said construction was that in practice it was found impossible to make 30 both screws seat, owing to difference of expansion and contraction from changes in temperature, and in keeping their seats free from dirt, it being difficult to get at the inner seat to keep it clean, and if not perfectly clean the 35 outer seat would not abut. For the above reasons the construction named has never come into general use.

My invention is shown in the accompanying drawing by a single figure, which is an elevation of the pin and a vertical section of the 40 box.

A is the box, and has two female screws, *a* and *a'*, of equal pitch but unequal diameters.

B B' is the pin, and is formed of two screws to connect with the two screws in the box, 45 being in effect a double or a shouldered pin. Between the two pins is a curved or braced shoulder, *b*, and at the base of the main pin is a second shoulder, *b'*. These latter add greatly to the strength of the pins. It will be 50 observed that the shoulder *b* has no seat, and that the only seat for the whole joint is at *s*. This is the essential feature of the construction, as it effectually overcomes the difficulties above named, and thus secures all the 55 benefits sought to be obtained by the construction. The curved or beveled shoulders *b* and *b'* are of great value, and especially the one at *b*. The one at *b'* may be omitted, if desired. The shoulder between the female screws *a* and 60 *a'* may be beveled also, but there should be no seat at that point.

What I claim as new is—

1. In a pin-and-box joint for well-drills, the combination, with the box A, having the two 65 female screws *a* and *a'*, of the pin B B', with beveled shoulders *b* and *b'*, said parts having a single seat, *s*, as set forth.

2. In a pin-and-box joint for well-drills, a pin consisting of the parts B B' and beveled 70 shoulders *b* and *b'*, in combination with a box, A, constructed, as shown, to receive said pin, with a single seat, *s*, for the purposes mentioned.

In testimony whereof I affix my signature in presence of two witnesses.

DUNCAN CAMERON.
